(57) **CLAIM**

The ornamental design for a Murphy dog bed, as shown and described.

DESCRIPTION

FIG. 1 is a perspective view of a Murphy dog bed showing our new design with the bed closed;

FIG. 2 is a front view of FIG. 1 with the bed closed;

FIG. 3 is a back view of FIG. 1;

FIG. 4 is a right side view of FIG. 1 with the bed closed;

FIG. 5 is a left side view of FIG. 1 with the bed closed;

FIG. 6 is a top plan view of FIG. 1 with the bed closed;

FIG. 7 is a bottom plan view with the bed open;

FIG. 8 is a perspective view showing the bed in open position;

FIG. 9 is a front view showing the bed in open position;

FIG. 10 is a right side view showing the bed in open position;

FIG. 11 is a left side view showing the bed in open position;

FIG. 12 is a top plan view showing the bed in open position; and,

FIG. 13 is a bottom plan view showing the bed in open position.

The broken lines on FIG. 8 that represent a bracket behind the bed after it is folded down are for illustration only and form no part of the claimed design.
